CONTAINER BAND AND FASTENER

John E. Erickson, St. Paul, Minn., assignor to
 Metz Container Company, St. Paul, Minn., a
 corporation of Minnesota

Application August 5, 1935, Serial No. 34,709

11 Claims. (Cl. 229—5.7)

This invention relates to an improvement in containers and fastening means for securing the cover upon the container. A feature resides in providing a laminated or fibre container with a reinforcing ring member having a nature adapted to fit and engage against the side wall of the container so as to hold the ring in place after it is forced into the desired position near the top or open end of the container.

10 This reinforcing ring means is formed with a cross-sectional shape so that it provides a spring means which causes the end of the ring, particularly the lower end, to engage into the wall of the fibre container so as to hold the reinforcing ring in place on the container after it has been forced into the desired position. This reinforcing ring is particularly adapted to tapered fibre containers, or any other container where it is desired to provide a reinforcing ring near the 15 open end of the container for reinforcing the container transversely through the same, and also reinforcing the upper open end of the container, and providing an annular shoulder which is adapted to be positioned in close proximity to the lower edge of the cover which depends down the side of the container.

Further, the invention includes a clip or fastener which is of a resilient nature and which is formed with a hook end on one end of the same to engage into the annular reinforcing ring, while the other end of the fastener is offset having an angular shape, together with anchoring means, so that when the same is forced over the upper marginal edge of the cover with the hook end 20 engaging the reinforcing ring, the clip will snap into place and lock the cover onto the container so as to close the container. The clip does not lock the cover so that the clip cannot be removed, but has a spring nature so that it clamps both the reinforcing ring and the top marginal edge of the cover in a manner so that it is necessary to pry the top edge of the clip upward before the clip can be released. In this manner the clip locks the cover to the container in a 25 simple and efficient manner, however, should it be desired to inspect the contents of the container, by forcing a tool under the upper edge of the clip it may be raised sufficiently to release it from the cover.

30 A further feature resides in the form of the reinforcing ring which provides an annular bead which projects from the body of the container directly beneath the lower edge of the cover and in close proximity to the same so as to ward off 35 any tendency of an article engaging under the

edge of the cover to lift the same from the container.

The other features and details of the container and fastener will be more fully defined hereinafter.

5 In the drawing forming part of this specification:

Figure 1 is a perspective view of my container, showing my fastener holding the cover in place.

10 Figure 2 is an enlarged sectional detail showing a form of the container, cover and the clip for holding the cover, together with the reinforcing ring around the upper end of the container.

15 Figure 3 is a similar enlarged section to Figure 2, showing the cover-attaching clip engaging the reinforcing ring at a different point from that shown in Figure 2.

20 Figure 4 illustrates a perspective view of the resilient clip used for attaching the cover to the container.

25 Figure 5 is a perspective view of a wire catch which is similar to the catch of Figure 4, excepting that it is in the form of a round wire instead of a flat catch member.

The container A is made of fibre or any other suitable material. When made of fibre it is composed of a series of layers of paper adhered together in a manner so as to cause the same to form virtually an integral side wall. The bottom portion of the same may be placed in the container in any suitable manner. The container A as illustrated, is of a tapered construction, where- 30 in the side wall 10 tapers to flare outwardly from the bottom toward the top. The bottom end of the container is provided with a lower rim portion 11 and by means of suitable staples 12 the inside bottom portion, not illustrated in the drawing, is secured to this lower rim so that the inner bottom which is not shown, will be spaced up from the lower bottom edge 13 of the container A.

35 The container A is adapted to be closed by the cover B which is made of fibre or of the same material as the body of the container. The cover is formed with a depending flange 14 which projects practically at right-angles to the body portion 15 of the cover. The flange 14 is bound with a metal sheathing 16 which is formed with a marginal annular flange portion 17 which closely engages and lies in a plane with the body 40 45 15 while the lower edge 18 is bound by the metal sheathing 16 by the crimped-in portion 19 which is crimped in around the lower edge 18 of the flange 14 of the cover. This provides a strong 50 55 and substantial cover construction wherein addi-

tional rigidity is supplied to the depending flange 14 by the sheathing cover 16.

A feature resides in providing a simple and substantial reinforcing ring which is adapted to be positioned closely adjacent the lower edge 18 of the cover B and this I have accomplished by forming a ring or band of sheet material C having a certain cross-sectional shape which causes this band to grip the side wall 10 of the container A so as to hold the band C securely to the side wall. The band C may be formed to engage a tapered side wall 10 or a perpendicular side wall on a cylindrical container. The band C is formed with a cross-sectional shape so as to provide a gripping edge 20 along the bottom of the same which engages into the side wall by the resilient or spring-like nature of the band between the arched portions 21 and 22. The upper edge 23 also engages into the side wall 10, however, the upper edge will have a slightly lesser gripping force into the side wall than the lower edge 20, owing to the larger arched portion 22 which controls the gripping of the edge 23. The gripping force of the edge 20 is controlled by the smaller arched portion 21, making the lower edge 20 more rigid than the upper edge 23. The arched portions 21 and 22 blend into each other through the connecting integral channel portion 24.

The reinforcing band C is formed of a thin metal so that when the arches 21 and 22 are formed therein the band will be stiffened thereby, as well as providing a series of spring arches such as 21 and 22, or obviously any number of arches may be formed therein to give the desired tension to the annular inner gripping edges 20 and 23. No portion of the reinforcing band C engages the side wall 10 of the container excepting the edges 20 and 23. Thus I provide a reinforcing band with spring arches between the ends so that the ends will grip into the container wall and hold the band C firmly in place against slipping after it has once been anchored into the proper position on the side wall 10.

A further feature of the invention resides in the simple, quickly operated clip catch D which may be made of the flat resilient metal, as illustrated in Figures 2, 3 and 4, or which may be made in the round wire form D', as illustrated in Figure 5. The band C may be formed with slots 25 at intervals in the channel 24 as illustrated in Figure 2, which are adapted to receive the hook end 26 of the clip D, as illustrated. The other end of the clip catch D is formed right-angular at 27 so as to fit over the marginal flange 17 and prong portions 28 are provided projecting inwardly from the right-angular bracket portion 27 of the clip D which engage into the body portion 15 of the cover B to lock the clip D in place.

In this form of the clip D the end 26 is hooked into the slot 25 and then by pressing on the upper shank of the clip adjacent the right-angular bracket portion 27, the prongs 28 are forced over the metal marginal flange 17 by reason of the spring nature of the clip and as soon as the prongs have passed over this metal flange 17 they will bite into the body of the cover B locking the clip D in position to hold the cover B securely attached to the container A. The inner edge 29 of the flange 17 forms a shoulder for the prongs 28 to engage against should any pulling force be exerted against the shank of the clip D by the hook end 26 and the prongs 28.

Any outward force on the shank of this charac-

ter will simply cause the hook end 26 and the prongs 28 to more forcefully engage to lock the cover B in place. When it is desired to remove the clip D it is only necessary to insert a screw driver or other wedge-shaped member under the bracket portion 27 to raise the prongs 28 out of engaging position or over the shoulder 29. The clip D may be made long enough so as to place the hook end 26 in position to engage in a lower slot 30 formed adjacent the lower edge 10 rather than engaging in the slot 25 as illustrated in Figure 3. It may be preferable to form the band C with slots 30 at the lower end so as to permit drainage of any moisture from beneath the band C. Therefore, I have illustrated this construction in Figure 3, however, the clips D are of the same form and character whether they are used in slots 25 or in the slots 30 excepting that the clip D in Figure 3 is longer than the one used in Figure 2.

Figure 5 illustrates the wire spring clip D' which has the hook end 26' formed on the lower end thereof and a prong 28' on the upper end. The bracket portion 27' is formed in a similar manner to the clip D. This clip D' is provided with a curved or arcuated portion 36 which is adapted to fit closely to the bead or arched portion 21. The shank portion of the clip or catch D or D' extends along the side of the flange 14, whereas the stiff or rigid bracket portion 27 or 27' extends over the right-angular shoulder of the cover and over the marginal flange 17 thereof.

It is a feature to provide the reinforcing band C with arches which form the annular beads 35 such as 21 and 22, shaped so that they project in stepped relation, that is, the lower arch 21 being smaller than the upper arch 22 up to the lower edge of the flange 14 of the cover. The reason for this formation in the reinforcing band C is not only to provide a reinforcing band around the container A but to provide a form in the reinforcing band which will ward off anything engaging under the lower edge 18 of the cover B.

In using containers like A of the flared type for butter or similar commodities, they are piled together in a car or are packed collectively in shipment, and the shifting of these containers is apt to cause one container to wedge against another container and some of the containers are inclined to raise while others are apt to crowd under the edge of the cover. With my reinforcing band C, I provide an annular guard around the lower edge of the cover which prevents or wards off anything engaging under the edge of the cover. It will also be apparent that the clip in securing the cover such as D or D', tends to hold the reinforcing ring C more tightly into engagement with the wall of the container even though force is directed against the cover to pull the same off of the container.

These features and details define a structure of certain forms of my container-reinforcing band and guard for the cover and the clip for attaching the cover against free disengagement. It is apparent that variations may be made without adhering strictly to the construction and design shown but having the principal features thereof, to those skilled in the art and within the scope of the following claims, such as would be fully within the invention herein set forth and as covered by the appending claims.

I claim:

1. A container including a body portion hav-

ing a tapered side wall, a reinforcing band adapted to engage about the side wall having a cross-sectional shape to provide a series of arched beads extending annularly around the container 5 which provide a spring nature to the band to cause the edges thereof to grip into the container when it is forced in position on the container wall, a cover for said container having a depending flange adapted to extend in close 10 proximity to said reinforcing band, and a clip having a resilient nature engaging said reinforcing band on one end and having a spring engaging arm engaging said cover marginally to grip into the same and hold the cover locked to the container by simultaneously engaging said reinforcing band.

2. A reinforcing band-like ring for a fibre container formed of sheet metal having a cross-sectional shape formed with a series of arches 20 which provide a spring means to the body of said reinforcing band to cause the edges of the band to grip by spring force into the wall of the container and position the band against slipping on the side wall of a container.

25 3. A clip for holding a cover on a container including a shank, a hook on one end, and a bracket end having depending prong means adapted to engage into the cover marginally thereof, said hook end adapted to engage a shoulder on the container when said prong means engage the cover.

35 4. A clip for holding a cover to a container comprising a spring shank, a bracket on one end of said shank, and a hook formed on the other end of said shank to provide a clip for securing a cover to a container which is adapted to spring into operative position.

5. A clip for holding a cover to a container in combination with a reinforcing band secured 40 to the container, said clip having a resilient shank, a rigid hook engaging end formed thereon, a prong means formed on the other end of said shank, and recesses formed in said reinforcing band secured to the container adapted to 45 receive the hook end of said clip first and then said prong means being adapted to spring into the marginal edge of the cover with the prongs engaging in the body of the cover to hold the same locked to the container.

50 6. The combination, a container having a side wall of a nonmetallic nature, a metallic reinforcing band secured to said side wall, said band having a series of arches formed therein to provide a spring engagement to the upper and lower 55 edges of said band which are adapted to bite into the wall of said container when said reinforcing band is moved into operative position, a cover for said container, a depending flange formed on said cover, a reinforcing sheathing formed over the top and depending flange of 60 said cover and around the lower edge of the flange of said cover, slot means formed in said

reinforcing band, and a resilient clip having a hook formed on one end and a prong formed on the other end adapted to lock said cover to said container, with the hook end of said clip secured in the slot of said band, and the pronged 5 end engaging over the reinforcing sheathing and biting into the cover to lock the cover to the container.

7. A container having a fibrous body and cover portion of a nonmetallic nature, said cover having an integral depending flange, a metallic sheathing formed over said flange and cover portion to reinforce the same, a reinforcing band having a series of annular ribs in the form of arches formed therein and adapted to be positioned on said container in close proximity to the depending edge of said cover flange, and clip means having hook means on one end and prong means on the other end for engaging said reinforcing band and cover respectively to 20 lock said cover to said container with said reinforcing band acting to ward off forces from against said depending flange of said cover.

25 8. A container including a body and a cover portion formed of nonmetallic material and having a peripheral flange depending therefrom, a metal reinforcing sheathing formed over the corner and lower edge of the flange of said cover, a reinforcing band-like guard positioned on the 30 wall of said body in close proximity to the depending flange of said cover, and a resilient clip engaging said reinforcing band and over the reinforced corner of said cover in closed position, and removable by springing said clip out 35 of engagement with said cover.

9. A reinforcing band for fibrous containers and the like including a thin sheet metal band member, a series of longitudinally extending ridges formed in said band, a pair of spaced biting edges on said band for engaging the container to hold the reinforcing band in place, 40 and one of said ridges being larger than another.

10. A reinforcing metallic band for fibrous and nonmetallic containers including a body portion formed with a series of annular ribs or arches 45 between the side edges thereof, said arches providing side edges of said reinforcing band adapted to engage into the container to which the band is attached under spring tension to hold the same in operative position.

50 11. A reinforcing band for a container having a band-like body portion, a series of arches formed in said body portion between the sides thereof, inwardly engaging edges adapted to engage the sides of the container to which the band is adapted to be attached under spring tension by reason of the arches formed therein, 55 said arches acting as a guard for warding off forces against the lower free edge of the cover used on the container on which the reinforcing 60 band is positioned.

JOHN E. ERICKSON.
